POCKET RESPIRATOR

Robert B. Haller, Wilkinsburg, and William P. Yant, Murraysville, Pa., assignors to Mine Safety Appliances Company, Pittsburgh, Pa., a corporation of Pennsylvania

Application June 4, 1947, Serial No. 752,532

4 Claims. (Cl. 128—147)

1

This invention relates to respirators, and more particularly to respirators small enough to be carried in the pocket when they are not in use.

It is among the objects of this invention to provide a respirator which is very small and light weight, which is comfortable to wear, which is of simple but sturdy construction, which is inexpensive, and which includes a readily replaceable air purifying element.

In accordance with this invention, the body of the respirator is in the form of a cup disposed on its side so that it has a substantially vertical end wall from the edge of which an annular side wall projects laterally, preferably toward the wearer. An air purifying cartridge is removably mounted in the cup in sealing engagement with its side wall. The inner end of the cartridge is spaced from the end wall of the cup, and this space is connected with the outside of the cup by means of an air passage through the cup wall. A mouthpiece above the cup is connected by a tubular member with this air passage. The mouthpiece is held in the mouth of the wearer and may serve as the sole support for the respirator. The wearer breathes through his mouth, as his nose is closed by a clamp, and therefore inhales air through the cartridge, cup and tubular member connected to the mouthpiece. In some cases the wearer may exhale through the cartridge, while in others the respirator is provided with valves so that he inhales only through the cartridge. A strap may be attached to the respirator body for suspending the respirator from the neck of the wearer when the respirator is not in use. The respirator cup may take different forms. For example, it may be a rigid member into which the cartridge is screwed, or it may be a flexible member in which the cartridge is clamped.

The invention is illustrated in the accompanying drawings in which Fig. 1 is a rear view of a respirator with the carrying strap broken away; Fig. 2 is a side view with parts of the respirator shown in section; Fig. 3 is a plan view with the strap removed; Figs. 4 and 5 are views similar to Figs. 1 and 2, respectively, of a modified embodiment of the invention; Fig. 6 is an enlarged fragmentary vertical section of the second respirator; and Fig. 7 is a view similar to Fig. 2 of a further modification.

Referring to Figs. 1, 2, and 3 of the drawings, the body of a small respirator is in the form of a cup 1 turned on its side so that it has an upright end wall 2 encircled by a substantially cylind-

rical side wall 3. This cup is made from impervious flexible material, such as rubber. Removably mounted in the cup is a cylindrical cartridge 4 of well-known design which, as shown in Fig. 2, has perforated end plates 6 and 7 between which there is material 8 suitable for purifying the air that is to be inhaled through it. Where protection is desired from low concentrations of chlorine or sulphur dioxide, for example, iodized carbon may be used. However, the kind of air purifying material filling the cartridge has nothing to do with this invention.

The inner end of the cartridge must be spaced from end wall 2 of the cup to provide a chamber for the purified air to enter as it leaves the cartridge. For this purpose the inside of the cup is provided with an annular shoulder 9 that limits the distance the cartridge can be inserted in the cup. To hold the cartridge in the cup and to prevent leakage of air between their adjoining side walls, the annular side wall 3 of the cup is encircled by a clamping band 11, the ends of which are drawn together by a removable screw 12 in a well-known manner. The position 15 of the band along the cup can be controlled by providing the side wall with a pair of laterally spaced encircling ribs 13 between which the band is located.

The space or chamber between the inner end 20 of the cartridge and the end wall of the cup is provided with an air outlet or passage 14 (Fig. 3), preferably formed in the upper portion of the cup's side wall. Secured to the cup around this air passage and extending upwardly therefrom is a tubular member 16 which preferably curves back over the cartridge. Joined to the upper end of this member is a mouthpiece in the form of a surrounding flexible flange 17 from the end portions of which lugs 18 project 25 upwardly and rearwardly. The lugs are gripped between the teeth of the wearer with flange 17 inside the mouth between the teeth and lips. The lips surround the upper end of the tubular member so that the wearer can inhale through it to draw air through the cartridge, where it is purified, and then out of the cup through outlet 14. The respirator is supported by the mouthpiece with the upper part of the respirator body engaging the front of the chin. To keep the lower lip and chin out of contact with the metal cartridge, and also to make the respirator more comfortable to use, the upper part of the cup has an integral segment 19 that extends rearwardly over the upper edge of the cartridge. Extending downwardly from the rear edge of

this segment is a rubber pad 20 that spaces the cartridge from the chin. The front of the pad may be provided with integral projections 21 so that it will not obstruct the openings in plate 6.

Inhalation through the nose is prevented by means of a nose clamp which may take any of several different forms. The clamp shown in Figs. 1 and 2 consists of an arcuate coil spring 23 the downturned ends of which encircle stems 24 on opposed rubber discs 25. The two stems are pulled in opposite directions to separate the discs so that they can be slipped over the sides of the nose. The stems then are released, and spring 23 presses the discs against the nose to close the nasal passages. The clamp is attached to the rest of the respirator by a cord 26.

Although with certain chemicals in the cartridge, exhalation as well as inhalation can take place through the cartridge, other chemicals must not be subjected to the exhaled breath. Therefore, the respirator may be provided with valves to assure unidirectional air flow through the cartridge. One way of mounting the valves is to provide the inside of the cup with an annular groove in which a metal plate 28 is fitted tightly. The plate is spaced from the inner end of the cartridge and provided with a few centrally located inlets 29 which are covered by a flexible rubber valve diaphragm 30 in front of the plate. The center of the diaphragm is provided with a short headed stem 31 that extends through a central perforation in the plate to connect the diaphragm to the plate.

The end wall 2 of the cup is provided with a group of outlets 32 normally closed by a flexible rubber valve diaphragm 33 outside the cup. The center of the diaphragm is provided with a headed stem 34 that extends through a perforation in the cup to connect the diaphragm to it. The cup may be provided with a rib 35 encircling the exhalation valve to help protect it. Also, the inside of the end wall may be provided with a plurality of integral bosses 36 that engage plate 28 to prevent the end wall from being drawn against the plate when the wearer inhales.

The cup 4 preferably is provided with integral perforated lugs 38 on opposite sides of air outlet 14, and rings 39 are connected to these lugs and to the ends of any suitable carrying strap 40, preferably adjustable in length, that can extend around the neck of the wearer to support the respirator when it is not in use. While the respirator is being used, the strap may be placed over the wearer's head to relieve the wearer's mouth of some of the weight of the respirator.

In the embodiment of the invention shown in Figs. 4, 5, and 6 the cup 42 is rigid, preferably being formed from metal, and its annular side wall 43 is provided with screw threads for receiving the threaded inner end of an air purifying cartridge 44. As shown in Fig. 6, the distance the cartridge can be screwed into the cup is limited by a shoulder 46 with which the cup is provided some distance from its upright end wall 47. A gasket 48 is compressed between this shoulder and a shoulder 49 formed at the inner end of the cartridge to prevent leakage between them. Inside the cartridge a perforated plate 51 is held against shoulder 49 by the chemical 52, whereby the chemical is spaced from the inner end wall 53 of the cartridge. This wall is provided centrally with a group of inlets 54 normally covered by a flexible valve diaphragm 56 connected to the wall by a headed stem 57. With this arrangement a

new inhalation valve is used every time a cartridge is replaced.

5 The exhalation valve may be formed in the same manner, or it may be a separate unit mounted in a large opening in the end wall 47 of the cup. The valve shown has a body 58 of flexible material, such as rubber, provided with a surrounding groove 59 for receiving the cup's end wall. This body is provided with a group of outlet openings 61 through it, the outer ends of which normally are closed by a flexible diaphragm 62. The center of the diaphragm has an integral stem 63 that extends through the center of the valve body to connect them together.

10 Between the cartridge and the cup's end wall, the upper portion of side wall 43 of the cup is provided with an air outlet passage 65 surrounded by an upwardly projecting flange 66. Telescoped over this flange is a tubular member 67 which extends upwardly and rearwardly therefrom and carries an integral mouthpiece on its upper end. Like the mouthpiece previously described, this one consists of a longitudinally curved flange 68 provided with teeth engaging lugs 69 near its 15 opposite ends.

20 The side wall of the cup on opposite sides of the air outlet is provided with wire lugs 71 to which the ends of an adjustable carrying strap 72 are attached. A cord 73 hangs down from one of these wire lugs and supports a nose clamp which in this case is shown as being formed from a spring wire which is bent in such a manner as to provide a central coil 74 from which upwardly projecting, reversely bent portions 76 extend. 25 The ends of the wire extend downwardly from these portions and are hooked onto opposed parallel discs 77. An advantage of this clamp is that it can be operated by one hand by merely pinching upwardly projecting portions 76 together, which will spread the lower ends of the clamp farther apart and thereby separate discs 77 the amount necessary to receive the nose.

30 In the modification shown in Fig. 7 the distance that the cartridge 81 can be inserted in the flexible cup 82 is limited by a plurality of spacing members which may be in the form of bosses 83 integral with the end wall 84 of the cup. The cup's end wall may be provided with an exhalation valve 86 the same as shown in Fig. 2, although, if desired, it may be located at the center of the end wall as shown. The inhalation check valve is mounted in a convex plate 87, the edge of which is secured tightly to the cartridge case 88 around its perforated plate 89. The central area of the convex plate is provided with a plurality of inlets 91 normally closed by a flexible diaphragm 92 held against the inner surface of the plate by a headed stem 93 projecting through an aperture in the plate. As in the Fig. 5 embodiment of the invention, a new inhalation valve is used every time the cartridge is replaced by a fresh one, because the valve is connected permanently to the cartridge.

35 It will be seen that all of the respirators disclosed herein are of such a shape that the respirator body rests against the chin to ease the load on mouth and teeth. This is due to the fact that the tubular member above the cup extends upwardly and rearwardly from the front of the cup to the mouth.

40 According to the provisions of the patent statutes, we have explained the principle and construction of our invention and have illustrated and described what we now consider to represent its best embodiment. However, we desire to have

it is understood that, within the scope of the appended claims, the invention may be practiced otherwise than as specifically illustrated and described.

We claim:

1. A respirator comprising a cup having a substantially vertical end wall from the edge of which an annular side wall projects laterally, an air purifying cartridge removably mounted in the cup in engagement with its side wall but spaced from said end wall, the upper portion of said side wall between the cartridge and end wall being provided with an air passage, a mouthpiece above the cup connected to said passage, and an exhalation valve mounted on said end wall, said end wall being provided with an outwardly projecting protective rib surrounding the valve.

2. A respirator comprising a cup having a substantially vertical end wall from the edge of which a flexible annular side wall projects laterally, an air purifying cartridge removably mounted in the cup in engagement with its side wall and having a perforated inner end wall extending across the cup but spaced from said cup end wall, a clamping band surrounding said side wall for sealing it against the cartridge, a wall of the cup being provided with an air passage opening into the space between said end wall and cartridge, a tubular member connected to said passage and extending upwardly therefrom and over said cartridge and a mouthpiece above the cup connected to said tubular member.

3. A respirator comprising a cup having a substantially vertical end wall from the edge of which an annular side wall projects laterally, an air purifying cartridge removably inserted in the cup in engagement with its side wall and having a perforated inner end wall extending across the cup, bosses mounted on said cup end wall and projecting toward the cartridge to space the cartridge from said cup end wall, a wall of the cup being provided with an air passage opening into

the space between said end wall and cartridge, and a mouthpiece above the cup connected to said passage.

4. A respirator comprising a cup having a substantially vertical flexible end wall from the edge of which a flexible annular side wall projects laterally, an air purifying cartridge removably mounted in the cup in engagement with its side wall, a clamping band surrounding said side wall for clamping it against the side of the cartridge, bosses in the cup integral with said end wall and projecting toward the cartridge to space it from said end wall, the upper portion of said side wall being provided with an air passage, a tubular member connected to said passage and extending upwardly therefrom and over said cartridge, and a mouthpiece mounted on the upper end of said member.

ROBERT B. HALLER.
